UNITED STATES PATENT OFFICE

CARL HESTON ASA E. CASADY AND HUBERT W. PIERSON, OF SAN DIEGO, CALIFORNIA

CARPENTER'S CLAMP

Application filed June 21, 1924. Serial No. 721,433.

Our invention relates to a carpenter's clamp, particularly adapted for supporting doors, windows, boards, and the like on one edge while planing or otherwise working on the same, and the objects of our invention are: First, to provide a clamp of this class which is provided with a pair of jaws, the one of which is adapted to secure the clamp to the beam of a trestle or other similar object, and in the other jaw of which is adapted to be secured the one end or edge of a door, window, board or other work while planing or otherwise working on the same; second, to provide a clamp of this class having two jaws so positioned relatively to each other that the same may be used interchangeably for supporting the clamp in different positions, whereby wide as well as relatively narrow doors, windows and the like may be planed or worked upon as desired; third, to provide a clamp of this class which may be supported at its one end on the beam of a trestle or other object and extended upwardly therefrom in such a manner as to support a door or the like at its one end intermediate the adjacent side edges; fourth, to provide such a clamp which may be supported flat against a beam for supporting relatively narrow members in an upright position while planing or otherwise working upon the same; fifth, to provide a novelly constructed carpenter's clamp, and sixth, to provide such a clamp which is very simple and economical of construction, durable, light, compact, practical, and which will not readily deteriorate or get out of order.

With these and other objects in view, as will appear hereinafter, our invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a side elevational view of our carpenter's clamp supported on a trestle, shown fragmentarily, and supporting the one end of a door, also shown fragmentarily; Fig. 50 2 is an end elevational view thereof, showing

the door and the beam of the trestle in section; Fig. 3 is a top view thereof, showing one of the screws partially broken, and Fig. 4 is a side view of our clamp, showing the same secured to a beam in a different manner. 55

Like characters of reference refer to similar parts and portions throughout the several views of the drawings.

The clamp member 1, screws 2 and 3, movable jaw members 4 and 5, and the handle members 6 and 7, constitute the principal parts and portions of our clamp. 60

The member 1 of our carpenter's clamp is preferably cast in one piece and consists of the spaced apart clamp portions 1^a and 1^b supported relatively to each other by the T-shaped connecting portion 1^c. The front side of the portion 1^c forms a relatively long, flat abutment face. The clamp portion 1^a consists of a stationary jaw portion 1^d and a screw supporting portion 1^e, both of said last mentioned portions extending outwardly from and at a right angle to the abutment face of the T-shaped connecting portion 1^c at one end thereof. The screw supporting portion 1^e is also spaced a considerable distance from the jaw portion 1^d in a lateral direction and from the main portion of the connecting portion 1^c. In the screw supporting portion 1^e, which is provided with an outwardly extending boss, is mounted the screw 3, at the end of which, extending toward the jaw member 1^d, is rotatably mounted the movable jaw member 5 in the form of a disc, the screw 3 being preferably reduced in diameter at said end and riveted over at the inner side of the jaw member 5 in such a manner as to permit rotation of the screw 3 and member 5 relatively to each other. At the outer end of the screw 3 is provided a handle member 7 for rotating the screw. 70 75 80 85

The end of the connecting portion 1^c opposite the clamp portion 1^a is provided with a rearwardly extending arm 1^f forming a substantial, flat base at right angles to the abutment face of the portion 1^c, and adapted to support the latter in an upright position. The clamp portion 1^b provided at said last mentioned end of the connecting portion 1^c consists of a stationary jaw portion 1^g and a 90 95 100

screw supporting portion 1^b. Said last mentioned jaw and screw supporting portions 1^a and 1^b, respectively, extend longitudinally relatively to the connecting portion 1^c and beyond the one end thereof so that the clamp may be rigidly secured to a beam B of the trestle T or any other similar object, when said clamp is positioned in an upright manner on said last mentioned end, the base 1^c forming the abutment face of the clamp 1^a.

It will be noted that the screw supporting portions 1^a and 1^b are extended laterally a considerable distance from the main longitudinal portion of the connecting portion 1^c, so that a door D, secured at its one end in the clamp portion 1^a, is adapted to rest at its lower edge on the top side of the beam B, as shown in Figs. 1 and 2.

In the screw supporting portion 1^b is mounted a clamp screw 2 which is provided at the end extending toward the stationary jaw portion 1^c with a movable and relatively rotatable jaw member 4. At the outer end of the screw 2 is also provided a handle member 6 for rotating the same.

It will be noted that the screws 2 and 3 extend in the same general direction relatively to the connecting portion 1^c permitting the clamp portions 1^a and 1^b to be opened transversely relatively to said connecting portion in such a manner that the door or other object supported by one of the clamp portions may be supported on or against the clamp supporting means and in alignment therewith.

On the inner faces of the stationary jaw portions 1^a and 1^b, as well as the movable jaw members 4 and 5, are preferably secured rubber or other pads to protect the objects clamped.

Figure 4 shows the clamp secured to the beam B against the long flat portion of the T-shaped connecting portion 1^c by means of the clamp portion 1^a. This position of the clamp permits an object of considerably less width to be supported on its one edge while planing the opposite edge thereof, the extended portion 1^c serving as a stop for the end of the object to be planed. It will be noted that our clamp may be secured near the one end of the beam of a trestle in the position as shown in Fig. 4 but with the clamp portion 1^b extending beyond the end of said beam so that an object, such as a wide door or window, may rest with its one edge on the floor.

It is obvious from this construction, as illustrated in the drawings and disclosed in the foregoing specification, that there is provided a carpenter's clamp as aimed at and set forth in the objects of the invention, and though we have shown and described a particular construction, combination and arrangement of parts and portions, we do not wish to be limited to this particular construction, combination and arrangement, but de-

sire to include in the scope of our invention the construction, combination and arrangement substantially as set forth in the appended claims.

Having thus described our invention, what we claim as new and desire to secure by Letters Patent, is:

1. In a carpenter's clamp, a clamp member provided at one side near one end with a stationary jaw having a face extending in the general direction of said clamp member and also provided at said end with a screw supporting portion at a spaced distance from said jaw and the main portion of said clamp member, a screw operated jaw movably mounted relatively to said stationary jaw, the axis thereof extending transversely with the main portion of said clamp member, said clamp member being provided at its opposite end with another stationary jaw extending beyond said end thereof, said clamp member being also provided with another screw supporting portion at said last mentioned end at a spaced distance from said last mentioned stationary jaw, and a movable screw operated jaw movably mounted in said last mentioned screw supporting portion relatively to said last mentioned stationary jaw, the longitudinal axis of said last mentioned movable jaw extending transversely with the main portion of said clamp member, said last mentioned stationary jaw and movable jaw being positioned to one side of the normal engaging face of said clamp member.

2. In a clamp of the class described, a jaw supporting and connecting member having two angularly disposed straight, flat abutment faces, a yoke at the one end of each of said faces, the inner surface of said yoke lying in the plane of the respective abutment faces, a stationary jaw integral with each of said yokes, and adjustable jaws cooperatively mounted therewith, the faces of said jaws lying in parallel planes.

3. In a clamp of the class described, a jaw connecting and supporting member comprising two portions having straight abutment faces extending substantially at right angles to each other, a clamp yoke at the outer end of one of said portions and a second clamp yoke at the inner end of said second portion, the inner faces of said yokes lying in the plane of the respective abutment surfaces and extending laterally therefrom, a clamp jaw integral with each of said yokes and adjustable jaws cooperatively mounted therewith, said jaw faces lying in parallel planes.

4. In a clamp of the class described, a jaw supporting member comprising two right angularly disposed portions of different length, said portions forming straight, flat abutment faces on their outer sides, a clamp yoke at the outer end of the longer portion, a second clamp yoke at the inner end of the shorter portion, the inner surfaces of said yokes co-

inciding with the corresponding abutment faces, and clamp jaws supported on said yokes, the faces of said jaws lying in parallel planes.

5 In testimony whereof we have hereunto set our hands at San Diego, California, this 9th day of June, 1924.

CARL HESTON.
